UNITED STATES PATENT OFFICE.

HARRY P. TABER, OF WILMINGTON, DELAWARE.

SYSTEM OF TREATING OIL.

Application filed August 19, 1921. Serial No. 493,604.

This invention relates to an improved means for and method of treating oil, and more particularly to the treatment of such oils as linseed and China wood, and other 5 so called drying or semi-drying oils.

In the making of varnishes, printing inks or other substances which have for their base or part of their make-up, linseed, China wood, poppy seed, or any of the so-called 10 drying or semi-drying oils, it has been the practice, and often necessary, to "body" or thicken these oils by oxidation, such as by "blowing" with air, boiling, or by applied mechanical means. Often in systems as 15 heretofore conducted, lack of attention, over-heating, under-development, or other causes have resulted in an unsatisfactory product which in many instances has been a spoiled product. In the case of China wood oil particularly, when the same is subjected to a 20 temperature which is too high, or brought to a lower temperature but for too long a time, it polymerizes, and the batch of oil is thus ruined for varnish purposes.

25 One object of my present invention is to obviate the difficulties and defects in the treatment of oils to "body" the same as heretofore practiced, and to so treat the oil that the element of danger shall be reduced 30 to a negligible quantity, and to insure the obtaining of a product which shall be uniform throughout.

A further object is to so treat oil of the character specified that a continual flow of 35 oil may be had, and so that every part of the oil shall, during such flow, be subjected to air and also brought to a temperature previously decided upon and for any length of time which may be found necessary for 40 the proper "bodying" or thickening of the oil.

With these and other objects in view, the invention consists in certain features as hereinafter set forth and pointed out in the 45 claims.

In the accompanying drawings, which show an embodiment of an apparatus with which my invention may be carried into effect; Figure 1 is a sectional view; Figure 50 2 is a perspective view of the tank, and Figure 3 is a perspective view of a plurality of dividing partitions and means for supporting the same.

1 represents an elongated tank which may 55 be made of suitable metal and disposed over a source of heat. Such source of heat may

be a heated oil bath as indicated at 2, and the oil of this bath may be heated by any suitable gas heater 2^a or electric or other heater, or the tank may be heated directly 60 with the use of such heater located under said tank.

In the embodiment of the invention shown in the drawings, the tank 1 is divided by a plurality of partitions 3, 4, 5, 6, which 65 extend upwardly from the bottom of the tank and terminate at their upper edges below the plane of the open top of the tank. The upright partitions are so disposed as to form chambers or compartments 7, 8, 9, 70 10, 11—the two end chambers or compartments 7 and 11 being each one-half the width of the others.

A frame consisting of parallel bars 12 are disposed over the tank and may rest freely 75 on the ends of the latter. The frame bars 12 have secured to them, the upper edges of partitions 13, 14, 15 which depend into the chambers 8, 9, 10 and divide said chambers into chambers of the same size as the end 80 chambers 7 and 11. The partitions 13, 14, 15 are sufficient in length to extend from one side wall to the other of the tank and are of such depth as to terminate above the bottom of the tank, thus permitting the 85 chambers at respective sides of each partition 13, 14, 15 to communicate with each other at the bottom of the tank.

Oil from a suitable supply, indicated at 90 16, is provided to discharge in the first compartment 7 and a discharge outlet 17 is provided to receive treated oil from the last compartment 11 and deliver it to a suitable container or to a condenser or other suitable 95 device to effect rapid cooling.

It is evident that oil discharged into the first compartment must, in order to reach the discharge outlet 17, flow over the top edges of the partitions 3—6 and under the lower edges of the depending partitions 13—15, and that the rate of flow may be regulated 100 by vertically adjusting the partitions 13—15. This may be accomplished by raising or lowering the frame bars 12 and supporting them in adjusted position in any suitable 105 manner. The flow of oil may also be controlled at the source of supply by means of any suitable valve device.

In the operation of the apparatus, I cause 110 the oil to be treated to flow into the compartment 7 permitting it to overflow the partition 3 and enter the next compart-

ment, from which it will pass, under the partition 13, to the next compartment and after filling the latter it will overflow the portion 4 and enter the next compartment, 5 and so on to the end compartment 11 of the tank, from which latter it will flow to the receiving means for finished oil,—the body of oil under treatment being thus caused to be subjected alternately to the heat at the 10 bottom of the tank and exposed to the atmosphere to effect oxidation. It is apparent that in the flow of the oil through the apparatus, every part of it must come in contact with the heated bottom of the 15 tank when it flows under the depending partitions 13—15, and it is also evident that every part of the oil must be exposed to the air as it flows over the partitions 3—6. The alternate contact with heat and air 20 brings about a more rapid and efficient oxidation or bodying of the oil than when oil is treated by the methods heretofore employed, and gives a uniformity of treatment which has not heretofore been accomplished, so far as I am aware.

The rate of flow of the oil may be regulated as previously stated and it is evident that the temperature at which the oil is to be treated may be regulated by controlling, 30 by any suitable means, the heat source. With the use of my improved system, the oil may be heated from 350° to 600° F. It is evident that when the proper degree of heat for the particular bath of oil to be 35 treated, has been determined and obtained; the length of time the oil should be treated has been determined, and the rate of flow adjusted, it is possible to obtain a continuous flow of heat-treated oil from the apparatus. 40 For example, let it be assumed that the supply tank when filled and ready to flow, contains one gallon of oil, and that it is desired to bring the oil to a temperature of 200 degrees for ten minutes. The heat will be 45 adjusted to 200 degrees, the rate of flow so set that one gallon will flow through the apparatus in ten minutes (this gallon representing the cubic contents of the treating tank) and if the supply tank is allowed to 50 furnish a continuous stream of oil, there will be also a continuous stream of heat-treated oil flowing from the outlet of the

treating tank, and every part of the oil will have been brought in alternate contact with air and with heat for the period decided upon and at the temperature desired. 55

As different oils and different batches of the same type of oil may require different degrees of oxidizing or bodying treatment for various uses, I do not confine myself to an apparatus having any particular number of compartments, or to an apparatus of any specific size or form.

Various changes might be made in the details of my invention without departing 65 from the spirit thereof or limiting its scope and hence I do not restrict myself to the precise details herein set forth.

Having fully described my invention what I claim as new and desire to secure by Letters Patents, is:—

1. The method of treating drying oils which consists in establishing a continuous gravity flow of an undivided body of oil and subjecting the flowing body of oil alternately to the action of heat and air. 75

2. The method of treating drying oils which consists in establishing a continuous gravity flow of an undivided body of oil, repeatedly subjecting the flowing body of oil to the action of heat, and subjecting the flowing body of oil to the action of air after each heat treatment. 80

3. The method of treating drying oils which consists in establishing a continuous gravity flow of an undivided body of oil over a path extending alternately downwardly and upwardly, and subjecting the flowing body of oil to the action of heat at the low points of its path and to the action 85 of atmospheric air at the high points of its path. 90

4. The method of treating drying oils which consists in causing an undivided body of oil to flow continuously by gravity 95 alternately in contact with and away from a heated surface, and exposing the body of oil to the action of atmospheric air in the intervals when it is away from the heated surface. 100

In testimony whereof, I have signed this specification.

HARRY P. TABER.
